UNITED STATES PATENT OFFICE.

GEORGE S. ZAHNISER, OF NEW CASTLE, PENNSYLVANIA.

ANTI-RAIL-CREEPER.

No. 911,356.

Specification of Letters Patent.

Patented Feb. 2, 1909.

Application filed May 6, 1908. Serial No. 431,260.

To all whom it may concern:

Be it known that I, GEORGE S. ZAHNISER, a citizen of the United States of America, residing at New Castle, in the county of Lawrence and State of Pennsylvania, have invented certain new and useful Improvements in Anti-Rail-Creepers, of which the following is a specification, reference being had therein to the accompanying drawing.

10 This invention relates to anti-rail creepers, and the primary object of my invention is to provide a simple and inexpensive device for preventing a rail from creeping upon a tie or similar support.

15 A further object of this invention is to provide a simple, inexpensive and durable device that can be easily and quickly applied to rails to prevent longitudinal displacement of the same.

20 My invention aims to prevent rails from creeping particularly at joints or rail connections, it being a well known fact that the movement of a train approaching a rail connection often causes the same to buckle and 25 in many instances accidents occur, causing destruction of life and property.

In devising my improvement, I have provided a structure that binds a rail to a tie and prevents the same from creeping, a single 30 structure being used to prevent a rail from creeping in one direction and two structures to prevent a rail from creeping in either direction. It is optional with the superintendent of the track construction as to which 35 is used.

With the above and other objects in view, which will readily appear as the invention is better understood, the same consists in the novel construction, combination and arrangement of parts to be presently described and, then specifically pointed out in the appended claims.

Referring to the drawings forming a part of this specification, Figure 1 is a side elevation of two connecting rails equipped with my anti-creepers. Fig. 2 is a similar view of a single rail equipped with the anti-creepers. Fig. 3 is a cross sectional view taken on the line $x-x$ of Fig. 2 looking in the direction of the arrow of said figure, with the tie thereof in dotted lines in the foreground. Fig. 4 is a cross sectional view taken on the line $y-y$ of Fig. 2 looking in the direction of the anti-creepers. and Fig. 5 is an elevation of the

inner side of one of the members of the anti-creepers.

In the accompanying drawings, 1 designates the confronting ends of rails, which I have conventionally illustrated as connected together by splice bars 2, bolts 3, and nuts 4, 60 said rails being supported by ties or sleepers 5 and 6.

In connection with the rail joint, I use anti-creepers that are located at the sides of the ties 5 and 6, to prevent the rails from 65 creeping or becoming longitudinally displaced. Each anti-creepers comprises two complementary members 7 and 8 and each member is formed with a tie bearing surface 9, with a transverse opening 10, and with a 70 groove 11, the upper and lower faces of the groove 11 being serrated or toothed, as at 12. The forming of the groove 11 in the members 7 and 8 produces gripping jaws to engage the base flanges of the rails and holds said rails 75 against creeping. The outer face of each member is cut away, as at 13 to reduce the weight of the same, and the members of each anti-creepers are connected together under each rail by a bolt 14 and a nut 15. The 80 grooves 11 are formed at right angles to the tie bearing surfaces 9, with the body of each member disposed at an angle to the tie bearing surfaces, whereby when the members are placed in engagement with the rails, said 85 members will be disposed at an angle to a tie, the object of which will presently appear.

The grooves 11 of the members are adapted to receive the base flanges 16 of the rails, and the serrated or toothed upper and lower 90 surfaces of the grooves are adapted to prevent a rail from sliding in said grooves. Consequently a movement of a rail longitudinally is prevented by the angularly disposed members binding against a tie, and 95 such a movement tends to more firmly hold the rail upon the tie.

In Fig. 2 of the drawings I have illustrated a single rail and one anti-creepers can be advantageously used particularly when trains 100 travel in one direction upon the rail, it being only necessary to locate the anti-creepers upon the side of the tie facing the approach of trains.

I have illustrated two of the sides of the 105 anti-creepers as being reinforced by ribs, these ribs adding rigidity and insuring stability.

My rail anti-creepers is constructed of

strong and durable metal and the simplicity of construction permits of the same being easily and quickly placed in engagement with a rail and tie, without damaging or modifying the construction of either.

Having now described my invention what I claim as new, is:

1. An anti-creeper for rails comprising two complementary members extending outwardly at an inclination with respect to a tie and each having the lower inner corner thereof cut-away to provide a perpendicular tie-bearing surface, each of said members further having its inner face provided with a horizontally disposed groove to receive one side of a base of a rail, each of said corners of a length equal to the width of the inner face of its respective member.
2. An anti-creeper for rails comprising two complementary members extending outwardly at an inclination with respect to a tie and each having the lower inner corner thereof cut-away to provide a perpendicular tie-bearing surface, each of said members further having its inner face provided with a horizontally disposed groove to receive one side of a base of a rail, each of said corners of

a length equal to the width of the inner face of its respective member, and each of said members further provided on that face 20 which opposes the tie with a reinforcing rib.

3. An anti-creeper for rails comprising two complementary members extending outwardly at an inclination with respect to a tie and each having the lower inner corner thereof 35 cut-away to provide a perpendicular tie-bearing surface, each of said members further having its inner face provided with a horizontally disposed groove to receive one side of a base of a rail, each of said corners of 40 a length equal to the width of the inner face of its respective member, each of said members further provided with an opening extending at right angles with respect to the length of the groove, and means for coupling 45 the members together thereby clamping the rail thereto.

In testimony whereof I affix my signature in the presence of two witnesses.

GEORGE S. ZAHNISER.
